GAS EQUALIZER FOR INTERNAL COMBUSTION ENGINES

William N. Cook, Battle Creek, Mich.

Application August 29, 1932. Serial No. 630,837

6 Claims. (Cl. 48—180)

This application is a continuation in part of my application Serial No. 556,795, filed August 13, 1931, for Gas equalizer for internal combustion engines.

5 The objects of this invention are:

First, to provide a device for breaking up and diffusing the mixture of air and fuel used in an internal combustion engine.

Second, to provide such a device that assures

10 a stable mixture.

Third, to provide such a device that removes from such mixture the entrained fuel and delivers to the engine a dry mixture.

Fourth, to provide such a device that assures 15 complete lubrication by eliminating fuel in the fluid state from the mixture fed to the engine.

Fifth, to provide such a device that can be easily and quickly installed in any automobile engine or other internal combustion engine.

20 Sixth, to provide such a device that may be cheaply manufactured.

Further objects and advantages of construction and operation will appear from the description to follow. A preferred embodiment of my 25 invention is illustrated in the accompanying drawing, in which:

Fig. 1 is a sectional elevation of my device in position in the manifold of an internal combustion engine, taken on line 1—1 of Fig. 2.

30 Fig. 2 is a bottom plan sectional view taken on line 2—2 of Fig. 1.

Fig. 3 is a view showing some of the various parts of my device separated, but in their relative positions.

35 Fig. 4 is a sectional view of my device showing a modified form of means for holding it in position.

Fig. 5 is a detail sectional view of the dished portion of one of the axial vanes, taken on 40 line 5—5 of Fig. 3.

The parts will be identified by their numerals of reference which are the same in all the views.

I show my invention in connection with a carburetor 1 of conventional form, shown in 45 dotted lines in Fig. 1, and an intake manifold 2 of an internal combustion engine having an up-draft portion 3 secured by flange 4 to flange 5 on said carburetor by means of bolts 6. Gaskets 7 are provided between said flanges.

50 My invention consists of a plurality of crossed metal strip members 8 having their ends spirally twisted a half turn or more to form blades 9. The members 8 are arranged criss cross so that a member having a plurality of spirally 55 twisted blades 9 is disposed across the up-draft

portion 3 of the intake manifold with the ends of the blades 9 touching or in close proximity to the walls of the up-draft portion. Depending and diverging from said members 8 are a plurality of vanes 10 reaching to the walls of the up-draft portion 3. The vanes 10 are spirally twisted about one quarter turn or more and are formed from strips of metal 11. A strip of metal 12 is bent to form vanes 10 having projecting feet 13 adapted to be clamped between gaskets 7 and flanges 4 and 5 to hold the device in position. The diverging vanes 10 thus form a frame of the shape of a frustum of a cone or pyramid.

Extending axially of this frustum are vane 14 twisted lengthwise to give them a spiral form, the spirals being in opposed relationship so that each gives a different swirl to the mixture engaged by them. The vanes 14 and 15 are formed from a strip of metal 16. Apertures 17, 18, 19 and 20 are provided respectively in members 8, 11, 12 and 16 for the reception of a rivet 21 that binds the members together to form my device. Any suitable fastening means can be used instead of the rivet 21.

In the modification shown in Fig. 4 the members 108 have projecting therefrom flattened portions 109 adapted to be clamped between flanges 104 and 105. This construction is for use in engines in which the up-draft portion 103 of the manifold is joined to the manifold 102 as is shown in Fig. 4, where there would be no place to position the feet 13 of the type of device shown in Fig. 1.

I have found that the efficiency of the operation is increased if on vanes 14 and 15 I provide at least one dished portion 22 formed by striking up a portion of the metal. I have here shown the vanes 14 and 15 formed with one such dished portion but more can be provided as desired. I have found that my device is especially suited for motors having up-draft to the manifold and best results are there accomplished, although the device works well in motors having down draft or other types of manifolds.

In operation the mixture from the carburetor is shot in a jet 23 directly against the vanes 14 and 15 where it is swirled, forced outward and, at the same time, thoroughly broken up and diffused. The vanes 10, also tend to swirl the mixture and diffuse it when it impinges thereagainst as it comes from the carburetor or from vanes 14 and 15. When the mixture

passes through the vanes 10, 14 and 15, it strikes the blades 9 and is further broken up, diffused, and swirled.

When in operation the blades and vanes act as eliminator plates and remove from the mixture sent therethrough any drops of entrained fuel that would ordinarily pass directly to the cylinders of the motor. When used in an up-draft manifold the entrained fuel is intercepted 10 and runs down vanes 10, 14 and 15. When my device is viewed in operation through a glass the fuel can be seen running down the vanes 10 where it is again caught up by the mixture flowing through the manifold and is further 15 broken up and diffused.

The swirling motion given to the fluid passing through my device tends to send the drops of fuel by centrifugal force against the walls of the intake manifold where they condense out 20 of the mixture and run down until they are caught in the blast of the incoming mixture and are again acted upon by the device until thoroughly broken up.

In use I have found my device to be especially 25 effective because a thoroughly mixed homogeneous dry fuel and air mixture goes to the cylinders. Better power and a considerable saving in gasoline are thus effected, while the cylinder oil is able to fully lubricate the pistons 30 and the cylinders without dilution from the unburned fuel, and there is practically no carbon deposited from unburned fuel. Oil in the crank case of the engine does not become thinned and may be used indefinitely without 35 changing.

I have described my invention in the embodiment preferred by me but wish to claim the same broadly as well as specifically, as pointed out in the appended claims.

40 Having thus described my invention, what I claim as new and desire to secure by Letters Patent is:

1. In an apparatus of the class described, the 45 combination of a plurality of spirally twisted blades radially arranged and adapted to fit across the manifold of an internal combustion engine, a plurality of spirally twisted vanes depending and diverging therefrom to form a frustum shaped frame adapted to fit within the 50 walls of said manifold, and a pair of vanes extending from said blades substantially axially of said frame in the direction of said diverging vanes each twisted lengthwise to give it a spiral form opposed to the spiral form of the other 55 of said vanes and each having a dished portion.

2. In an apparatus of the class described, the 60 combination of a plurality of spirally twisted blades radially arranged and adapted to fit across the manifold of an internal combustion engine, a plurality of spirally twisted vanes depending and diverging therefrom to form a frustum shaped frame adapted to fit within the 65 walls of said manifold, and a pair of vanes extending from said blades substantially axially

65

70

75

of said frame in the direction of said diverging vanes each twisted lengthwise to give it a spiral form opposed to the spiral form of the other of said vanes.

3. In an apparatus of the class described 80 adapted to be fitted within the walls of the manifold of an internal combustion engine, the combination of a set of blades adapted to be disposed across the manifold and diverging from a common center and in a single plane, each blade having a surface disposed to intercept air flowing in said manifold through said set of blades and transversely of said plane, a set of vanes diverging from said common center to form a frustum shaped frame, each vane having a surface disposed to intercept air flowing from within said frame and to direct said air toward said set of blades, and a vane extending from said common center perpendicularly to said set of blades and within said frame and having a surface adapted to swirl air entering the open end of said frame and to direct it outwardly to and through said set of vanes.

4. In an apparatus of the class described 100 adapted to be fitted within the walls of the manifold of an internal combustion engine, the combination of a set of blades adapted to be disposed across the manifold and diverging from a common center and in a single plane, each blade having a surface disposed to intercept air flowing in said manifold through said set of blades and transversely of said plane, a set of vanes diverging from said common center to form a frustum shaped frame, each vane having a surface disposed to intercept air flowing 105 from within said frame and to direct said air toward said set of blades.

5. In an apparatus of the class described 110 adapted to be fitted within the walls of the manifold of an internal combustion engine, the combination of a set of blades adapted to be disposed across the manifold and diverging from a common center and in a single plane, each blade having a surface disposed to intercept air 115 flowing in said manifold through said set of blades and transversely of said plane, and a vane extending from said common center perpendicularly to said set of blades and within said frame and having a surface adapted to swirl air entering the open end of said frame and to direct it outwardly.

6. In an apparatus of the class described 120 adapted to be fitted within the walls of the manifold of an internal combustion engine, the combination of a set of vanes diverging from a common center to form a frustum shaped frame, each vane having a surface disposed to intercept air flowing from within said frame, and a vane 125 extending from said common center within said frame and having a surface adapted to swirl air entering the open end of said frame and to direct it outwardly to and through said set of vanes.

WILLIAM N. COOK.
